UNITED STATES PATENT OFFICE.

WILLIAM M. RAPP, OF ATLANTA, GEORGIA.

STREET-SERVICE BOX FOR WATER AND GAS.

1,032,503.

Specification of Letters Patent. Patented July 16, 1912.

Application filed October 4, 1910. Serial No. 585,184.

To all whom it may concern:

Be it known that I, WILLIAM M. RAPP, a citizen of the United States, and a resident of Atlanta, county of Fulton, State of Georgia, have invented an Improvement in Street-Service Boxes for Water and Gas, of which the following is a specification.

My invention has reference to street service boxes for water and gas and consists of 10 certain improvements which are fully set forth in the following specification and shown in the accompanying drawings which form a part thereof.

Heretofore it has been customary to provide 15 street curb water and gas service boxes, with removable top or lid with tap number on it, to designate the particular cock, for the convenience of the department, this top being held in its place by a screw. Much 20 inconvenience has resulted from the fact that the screw rusts in position, and also requires a special tool for removing it. It is often broken in being removed. The top or lid, with tap number, becomes lost, causing 25 a great inconvenience in locating the proper tap; and the box also becomes full of dirt, the obstructions thus caused necessitating the digging up of same.

The object of my invention is to provide 30 a construction of water and gas service box for curb cocks which shall be devoid of the objections above pointed out; and which shall, moreover, be cheap to construct, not liable to get out of order and which, if the 35 plug is lost, still retains the record or tap number of the curb cock.

My invention consists of a service box for 40 street water and gas curb cocks which is fully described hereinafter and more specifically defined in the claim.

Referring to the drawings: Figure 1 is a 45 sectional elevation of a water service box for street curb cocks embodying my invention; Fig. 2 is a plan view of the same with the plug removed; Fig. 3 is a plan view of the plug; Fig. 4 is a perspective view of the plug inverted; and Fig. 5 is a sectional elevation showing a modification of the curb box.

50 A is the curb cock and as ordinarily made, is provided with the threaded portion D. The service or curb box is provided with a pipe B extending down from the pavement and may be provided on the lower end with 55 a sleeve which is screwed upon it, the other end of the sleeve being screwed upon the

threaded portion D of the body of the curb cock A. Secured to the top of this tubular portion B is the top casting E of the service box, the union being made by fitting the 60 cylindrical socket F, on the under portion of the top casting, over the upper end of the tube and screwing it in place by a set screw G. The socket portion F is made of a very 65 loose fit upon the tube and is also of a depth to allow of vertical adjustment so as to compensate for any variation in the level of the street pavement relatively to the position of the curb cock. A set screw G may be arranged close to the bottom of the upper or 70 socket portion F so as to be always in position to clamp the top casting of the box upon the tube for all positions of adjustment. This construction permits the box to be extensible.

75 Referring more specifically to the top casting E and plug therefor, said casting is provided at the upper end of its socket portion F with an annular flange H having an aperture K in its center, said aperture being 80 above the opening in the upper end of the tube B forming the lower part of the box. The aperture K is of smaller diameter than the internal diameter of the socket portion F so as to provide an internal flange L which 85 is provided with an annular depressed upper surface and with a plurality of notched portions M (Fig. 2). The top outer flange H of the top casting has the letters spelling the word "Water" or "Gas," according to 90 the particular use, and the tap number of curb cock corresponding to the record number on the departments' records. The word "Water" or "Gas" is indicated at I and the number at J, said designations being preferably in relief, as shown in Figs. 1 and 2.

The plug N is cylindrical and provided 95 with a flange O at the top which fits the recessed flange portion L of the top casting E so as to have its upper surface preferably 100 substantially flush with the upper surface of said casting. The body part of the plug loosely fits the cylindrical aperture K in the top casting E and the lugs P of the plug pass downward through the notched portions M and, upon turning the plug, pass 105 under the flange L and thereby lock the plug from being withdrawn. The plug is made to form a snug fit into the seat on the top casting E but so as to be easily rotated 110 and withdrawn when required.

The upper portion of the plug is recessed

as at Q and provided with a cross bar R which acts as a handle to lift it and also to turn it, whether by hand or by the ordinary key which is used to turn the curb cock A. 5 These parts Q and R of the plug are below the upper surface so as not to project above the normal level of the pavement. The parts Q and R may be made in other ways, if so desired, so long as they provide a

10 recess and a part therein to receive a key. In practice, the dirt or rust will be amply sufficient to retain the plug in locked position as long as may be required; and when it is desired to remove the plug, this may 15 be easily done by using the regular key required for the curb plug A and without the necessity of any special tools. Under no conditions can the plug become so tightly held in the top casting but that it may be 20 easily removed; and to remove it, only requires a quarter turn instead of many turns. It is also evident that by placing the number of the curb cock on the flange H instead of on the top or lid as heretofore the loss of the 25 plug will not remove the tap record number. This is a matter of much importance, first, because of the impossibility of the key-man's locating the curb cock readily and, secondly, because to cast a new top or 30 lid with the special tap number, is both expensive and troublesome. The plug is the only part which can become lost and this frequently occurs; but, as all of the plugs 35 are alike, the replacing of the plug is a matter of only nominal expense.

In place of using the sleeve C for uniting the cock A to the pipe B, this may be dispensed with by expanding the lower end 40 of the tube B as indicated at C' in Fig. 5, the said part C' fitting over the cock A without being screwed upon it, which is not at all necessary because of the fact that the pipe B is firmly held in the ground and supported by the wide flanged top casting. Be- 45 cause of the cheapness of this construction, I prefer to employ it in connection with my

service box. In some cases the lower construction would have to be changed to suit the shape and form of the curb cock employed and hence I do not restrict myself 50 in this respect. The lower part B of the box may be made of cast iron instead of wrought tubing if so desired.

I have shown my invention in the form which I have found excellently adapted to 55 its commercial use and while I prefer the details shown, they may be modified within the scope of the claim without departing from the spirit of the invention.

Having now described my invention, what 60 I claim as new and desire to secure by Letters Patent, is:

In a curb box for valves of water or gas pipes, the combination of a pipe leading down to the curb cock, with a top casting 65 having a deep socket portion loosely fitting over the upper end of the pipe and adjustably clamped thereon and also having an extended outer flange portion of large radius provided with the official record marking 70 of the box to designate its location said top casting further having a central opening of small diameter bounded with an inwardly extending annular flange arranged below the upper surface of the extended flange 75 portion said annular flange having notches opening laterally into the central aperture on opposite sides thereof, and a removable flanged plug loosely fitting the central aperture so as to be below the upper surface of the 80 top casting and also having two oppositely arranged lugs integral with its lower part to pass through the notches in the annular flange of the top casting and engage the under side of the unnotched portions thereof 85 when the plug is turned.

In testimony of which invention, I hereunto set my hand.

WILLIAM M. RAPP
